Inventor,

Richard E. Nolley

UNITED STATES PATENT OFFICE.

RICHMOND E. NOLLEY, OF ATLANTA, GEORGIA.

AUTOMATIC SWITCH.

SPECIFICATION forming part of Letters Patent No. 391,064, dated October 16, 1888.

Application filed June 7, 1888. Serial No. 276,396. (No model.)

To all whom it may concern:

Be it known that I, RICHMOND E. NOLLEY, a citizen of the United States, residing at Atlanta, in the county of Fulton and State of Georgia, have invented a new and useful Automatic Switch; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The object of this invention is to produce an automatic switch that will operate in a way to set to the siding or main line on which a train may approach from one direction and that may be operated from the locomotive to cause the switch-rails to coincide with any of several tracks when the switch is approached from the other direction, and to operate a semaphore to indicate the track with which the switch-rails are connected.

It consists of the several parts hereinafter fully set forth.

In the accompanying drawings, Figure 1 is a plan of a main track and two sidings, the cams by which the gate-rails are moved, and the rock-shafts by which the cams are operated. The lower part of the semaphore-shaft and its bracket are shown in section on line xx , Fig. 3. Fig. 2 is a side view of Fig. 1 in section on the line yy , the rails A' and C' being removed. Fig. 3 is a vertical section through a portion of the frame that carries the cam-shaft, and further shows the connection of that shaft with the semaphore. Fig. 4 is a side view of one of the cams that move the gate-rails, both being alike. Fig. 5 is a view of the right-hand end of the cam shown in Fig. 4. Fig. 6 shows one of the levers on a rock-shaft and a portion of one of the depression-levers and the loops by which it is held in position laterally and guided in its vertical movement. Fig. 7 shows a section through the rock-shaft G on the line zz , showing the upwardly-projecting arm N . One of these arms projects upwardly from each of the three rock-shafts, and all are connected together by rods, as shown in Fig. 1, the arm on the middle rock-shaft having sufficient width to permit the attachment of both connecting-rods.

Fig. 8 shows an end view of the track and a truck on it carrying an adjustable roller that will depress either of the levers over which the roller runs in approaching the switch from the right, as it is shown in Figs. 1 and 2.

In the figures like reference-marks indicate corresponding parts in the several views.

A A' is the main track of a railway. B B' and C C' are side tracks. a and a' are gate-rails. The rock-shaft G is journaled in any suitable way. D, E, and F are depression-levers hinged to the rod g , a depression-lever being placed contiguous to the side of one rail of each track and rests on one of the levers H , as is shown in Fig. 2. The rock-shaft is preferably journaled to the rail in any suitable manner.

The shaft J is journaled in a frame that also carries the semaphore.

In this frame are the cross-pieces j , and on these cross-pieces are the projections k , Figs. 1 and 3, against which the cams K abut. It will be observed by reference to Fig. 1 that as these cams are turned in either direction the distance between the points at which they will impinge against the projections k remains the same, and that the revolution of the cams in either direction will cause a longitudinal movement of the shaft J equal to the inclination of the cams in the distance traversed by them. To the gate-rails a and a' are attached the abutting pieces k' , that impinge on the cams and cause the rails to be moved in their position to the cams as much as the inclination of the inner surfaces of the cams, the gate-rails being moved a distance equal to the inclination of both sides of the cams. The shaft J has an upwardly-projecting arm like that shown in Fig. 7, except that it has two connecting-rods attached to it, as shown in Fig. 1, the rod L connecting it with a similar arm on the rock-shaft G . The levers H , h , and h' are set at different angles on the shaft G , so that when one of the depression-levers is depressed, as shown in Fig. 2, the other depression-lever will be somewhat raised by the levers with which they are connected. For instance, in Fig. 2 the lever F is shown as depressed by the flange of the wheel running on the rail A' , Fig. 1. The depression of the lever H raises the arm N , Fig. 7, to an upright or middle position, and the connecting-rod L brings the lever of the rock-shaft J into the

same position, and the cams K move the gate-rails a and a' from any position to one that will cause them to coincide with the main-track rails A and A'. The longitudinal movement 5 of the shaft J turns the crank M of the semaphore through the connection m and the swivel m' . It is obvious that the depression of the levers h or h' will turn these cams, through the medium of the shaft G and arms N and the connecting-rod L, and shift the gate-rails one way or the other, as the case may be. The proportion 10 of all of these parts must be such as will cause the depression of one of the levers on the rock-shaft G to move the gate-rails just enough to coincide with the track on which 15 the wheel is running, which depresses by its flanges the depression-lever that causes the movement of the gate-rails.

The depression-lever belonging to the track 20 with which the gate-rails coincide will always be down, consequently the flange of the wheel will pass over it; but when a train approaches on one of the side tracks the flange of the first wheel running over the depression-lever belonging 25 to that track will depress the lever, and through the mechanism already described shift the gate-rails to connect with it and turn the semaphore by its crank and connection with the shaft J and cause it to indicate the position 30 of the gate-rails.

It will be best seen in Fig. 5 that the bosses on the inner ends of the cams K have several flat surfaces, f . Those surfaces are as many in 35 number as are the tracks with which the gate-rails connect, and the surfaces are so arranged as to rest flatly against the gate-rails when those rails are connected with either of those tracks. The principal function of these flat surfaces, on which the rails rest, is to prevent the 40 by superincumbent weight the rolling of the rock-shaft J by any lateral pressure that may come against the gate-rails. An incidental function of these flat surfaces is to prevent the friction of the gate-rails on the ties as they pass 45 from one position to another, as they are slightly raised in transit.

The rock-shaft P, preferably journaled in some suitable way to the rails A and A', carries levers O, o , and o' , Fig. 2, and is connected 50 through the arm N and the rod R with the arm of the rock-shaft J. The depression-levers S, T, and U move the gate-rails to make them coincide with the main line or siding corresponding to the lever in use in the same 55 manner as the depression-levers D, E, and F

have been above described as doing, except that either of the depression-levers S, T, and U is depressed as required by the roller W on the shaft w , attached to the locomotive or tender. The roller W slides lengthwise of the 60 shaft w to a position to engage with either of the levers S T U. This roller may be moved from one position to another in any suitable manner, according to the position in which it is placed on the locomotive or tender, it being 65 only desirable that it can be readily managed by the engineer. The gate-rails may be shifted by hand in many ways, one of which is to apply a removable lever in the form of a wrench to the flattened part j' of the shaft J. 70

The levers D, E, F, S, T, and U have attached to their bottoms the loops N' , Fig. 6, that go around the shafts and have sufficient length to allow the levers to rise to the required distance. One of these loops is on each side of each depression-lever and passes down both sides of each rock-shaft lever, thus preventing any undue lateral movement of the levers. 75

Having thus described my invention, what I 80 claim as new, and desire to secure by Letters Patent of the United States, is—

1. In an automatic switch, the gate-rails, the abutting pieces k and k' , and the cams K, arranged to operate simultaneously, for the purpose specified. 85

2. In an automatic switch, the rock-shaft J, the cams K, arranged to move the gate-rails a and a' , and the flat surfaces f , on which the gate-rails rest, substantially as shown and described, and for the purpose specified. 90

3. In an automatic switch, the gate-rails, the abutments k and k' , the cams K, the shaft J, the crank of a semaphore, and the connecting-rod m and swivel m' , substantially as shown and described, and for the purpose specified. 95

4. In an automatic switch, a depression-lever placed contiguous to the side of one rail of each track and arranged to be depressed by the wheel passing over it, several levers at different angles on the rock-shaft G, the shafts g and J, carrying arms N, connected by rod L, the cams K, the stationary abutments k , and the abutments k' , attached to the gate-rails. 100

In testimony whereof I hereunto affix my 105 signature in presence of two witnesses.

RICHMOND E. NOLLEY.
